(57) **CLAIM**

The ornamental design for a lamp, as shown and described.

DESCRIPTION

FIG. 1 is a top plan view of a lamp, showing the design. FIG. 2 is a front elevation view of the lamp of FIG. 1, showing the design.

FIG. 3 is a bottom perspective view of the lamp of FIG. 1, showing the design; and,

FIG. 4 is rear elevation view of the lamp of FIG. 1, showing the design.

The areas within the broken line boundaries in FIGS. 3 and 4 depict portions (specifically a bottom surface in FIG. 3 and a port opening in FIG. 4) of the lamp that form no part of the claimed design.

1 Claim, 4 Drawing Sheets
